WINDOW CONSTRUCTION

Tomlinson I. Moseley, San Francisco, Calif., assignor to Dalmo Sales Corporation, San Francisco, Calif., a corporation of California

Application April 22, 1935, Serial No. 17,640

10 Claims. (Cl. 189—67)

This invention relates generally to windows of the multiple sash type, in which the sashes are arranged to swing about generally horizontal axes. While not limited in its application, the 5 window disclosed herein is particularly suited for a construction of metal, as distinguished from the more common type windows which are usually made of wood.

It is an object of the invention to provide a 10 window of the above character utilizing vertically movable travel bars to interconnect the various sashes, which will afford smooth swinging action at all times, with a construction of great simplicity and reliability.

15 Another object of the invention is to afford a window construction which will facilitate assembling in manufacture, and which will permit the individual swinging sashes to be self-aligning in their relationship to the associated frame.

20 Another object of the invention is to provide a simplified automatic type of operating means for a multiple sash window, whereby a degree of selective operation is permitted by manipulation of one sash.

25 Further objects of the invention will appear from the following description, in which the preferred embodiment of the invention has been set forth in detail in conjunction with the accompany drawings.

30 Referring to the drawings:

Fig. 1 is a perspective view, illustrating a window incorporating the present invention.

Fig. 2 is a vertical cross-section of the window shown in Fig. 1, with the upper sash omitted.

35 Fig. 3 is a cross-sectional detail taken along the line 3—3 of Fig. 2.

Fig. 4 is a cross-sectional detail showing parts of the automatic operating mechanism together with details of the pivotal mounting of one of 40 the sashes.

Fig. 5 is a cross-sectional detail taken along the line 5—5 of Fig. 4.

Fig. 6 is a cross-sectional detail, with certain parts removed, showing the position of one of the 45 travel bars for full-open position of the sash.

Figs. 7 and 8 are cross-sectional details, similar to Fig. 6, but showing different operating positions for the parts.

Fig. 9 is a cross-sectional detail, showing the 50 pivotal connections of the two upper sashes in relation to the travel bar.

The window as illustrated in the drawings consists of a frame 10 which in this instance is formed of metal and is adapted to be mounted in 55 the wall 11 of a building. While the number of

sashes carried by the frame may vary, three sashes 12, 13 and 14 have been shown. The vertical side portions of the frame are formed of structural steel members 16, the cross-sectional contour in this instance being such as to afford 5 an intermediate web 16a, together with flanges 16b, 16c, 16d and 16e. Flanges 16b and 16e may be carried by a sub-frame formed of wood, which in turn is mounted in the building wall or may be directly embedded in the wall masonry. As will 10 be presently explained, flanges 16d and 16c form stops or jams to co-operate with the sashes, and at the same time afford inwardly spaced channels 17 extending vertically on both sides of the frame. Similar upper and lower horizontal members 15 15 form the ends of the frame, except that such members are arranged with their channels 17 faced outwardly. The left-hand side of the window, as viewed in Figs. 2 and 3, faces the exterior of the building, since it is customary to have the 20 sashes swing outwardly to open position.

Intermediate the top and bottom portions of the frame 10 are the horizontal members 18. A suitable cross-section for these structural members is illustrated in Fig. 2, in which it will be 25 noted that each member includes a web 18a, together with flanges 18b, 18c and 18d. The ends of these members 18 are suitably fixed to the vertical side members 16 of the main frame, as by welding.

The frame for each of the sashes 12, 13 and 14 includes upper and lower horizontal members 21, together with side connecting members 23. An intermediate bar 24 may extend between the members 21 to afford added rigidity. A suitable 35 cross-section for the members 23 is illustrated in Fig. 3, and includes the intermediate web 23a together with flanges 23b, 23c and 23d. The flanges 23c form ledges for engaging the edges of the glass panes 25. A suitable cross-section for 40 the members 21 is also shown in Fig. 2, and includes the intermediate web 21a, together with the flanges 21b, 21c and 21d.

The preferred manner of supporting the upper sashes 12 and 13 within the main frame can 45 be described as follows:— Referring first to the lower sash 14, the end portions of the upper members 21, illustrated in Fig. 4, are provided with pivot pins 26. As suitable means for mounting these pins, they are each shown carried with 50 in a metal tube 27, one end of which is flattened and secured to the member 21 by rivet 28. The other end of the tube 27 is shown extending through a plate 29, which in turn is fastened to the adjacent side member 23. A compression 55

spring 34 serves to normally urge pin 26 towards projected position. The outer end of pin 26 is of reduced diameter and extends into a shoe 32. This shoe is preferably channel-shaped, with its flanges 32a extending into the adjacent channel 17 to engage the tapered surfaces 33. Thus the shoes 32 may slide vertically within the channels 17 and at the same time the sashes may swing about the axes of pivot pins 26. The compression springs 31 serve to take up any lateral play and maintain the sashes properly aligned at all times, with a proper predetermined amount of friction between the shoes and the adjacent walls of the channels 17. Substantially identical pivot pin and shoe assemblies are provided for each of the upper sashes 12 and 13.

In addition to the pivot pin and shoe assembly described above, each sash is connected to the frame by supporting arms or links, to insure 20 swinging movement towards open position when the shoes are caused to slide with respect to the frame. Thus, for the lower sash 14 a pair of supporting links 36 are provided. The lower end of each of these links has a pivotal connection 37 to a plate 38, which in turn is fastened to the lower corner of the main frame. The upper end of each link 36 has a pivotal connection 39 with a sash plate 41, which in turn is mounted on the corresponding side member 23 of the sash, 30 at a point intermediate the upper and lower members 21. The upper sashes 12 and 13 are connected with similar supporting links 42. However, the lower portions 42a of these links are bent to extend inwardly and have pivotal 35 connections 43 with brackets 44. Brackets 44 are in turn mounted upon the inner faces of the side frame portions 16, being secured particularly to the flanges 16e (Fig. 3). In order that the links 42 may not interfere with proper swinging movement of the upper sashes 12 and 13, the inwardly extending portions 42a are shown accommodated in slots 46 (Figs. 2 and 3) which are cut in the flanges 16d. The offset or bent portions 42a for the links 42, which extend into 40 housings 45, make possible better application of forces to the upper sashes 12 and 13 to open and close the same. Thus, when forces are applied tending to slide the shoes 32 for the upper sashes downwardly, adequate force components are created tending to swing the lower edges of the sashes outwardly by virtue of the offset relationship of the pivotal connections 43.

The means provided for interconnecting all of the sashes is as follows:—Extending vertically 55 in the channels 17 are the travel bars 47. To facilitate making certain adjustments, to be presently described, each of these bars is preferably in three sections, designated 47a, 47b and 47c. Screws 48 accommodated in slots 49 serve to normally retain these sections together in fixed relationship. The upper section 47a of each travel bar extends through the corresponding shoe 32 for the upper sash 12 and is operatively connected to the same by upper and lower 60 shoulders 50a and 51a which project over and below the upper and lower ends of the shoe. Thus, the corresponding shoe is in effect locked within a recess on the travel bar, so that while it may independently align itself in engagement 65 with the surfaces of the adjacent channel 17, it is moved up and down by vertical movement of the travel bar. The connections between the middle travel bar section 47b and the shoes for the intermediate sash 13 are similar to the connections 70 previously described for the upper sash

12. Thus, shoulders 50b and 51b are provided, which extend over and below the upper and lower edges of the corresponding shoe 32.

The connections between the lower sections 47c of the travel bars and the lower sash 14 are such as to afford a clutch mechanism which is automatically engaged and disengaged, to cause a predetermined automatic cycle of operation. Thus, the lower extremity of each travel bar section 47c is provided with a recess 52, defined 10 by the upper and lower shoulders 50 and 51. The space between the shoulders 50 and 51 is only slightly greater than the length of the shoe 32 for the lower sash, so that these shoes may be accommodated in recesses 52 for conjoint 15 sliding movement with the travel bars. Such an engaged position is illustrated in Fig. 4. However, sufficient lateral movement is afforded for the lower travel bar sections 47c so that they can be swung to positions such as shown in Fig. 20 6, in which the corresponding shoe 32 is free to slide up or down without engaging the shoulders 50 and 51.

Automatically operating cam elements for effecting lateral swinging or swinging movement 25 of the travel bars are illustrated in Figs. 4 to 9 inclusive. Thus, in the embodiment illustrated, each travel bar section 47c carries a cam block 56, adapted to co-operate with the relatively stationary element 57. Element 57 can be in the 30 form of a metal strip or finger which is mounted near the end of a horizontal frame member 18, extending between the sashes 13 and 14. When sliding movement of a travel bar causes its cam block 56 to strike and ride over the end of the 35 corresponding finger 57, the lower end of the travel bar is swung laterally, thus effecting disengagement of the clutch mechanism formed by shoulders 50 and 51 in conjunction with the lower shoe 32.

Operation of my window construction can now be described as follows:—When all of the sashes are closed, the flanges 23b of the side sash members 23 are in relatively tight engagement with the frame flanges 16c, and likewise side flanges 45 23d of the sashes are in engagement with flanges 16d of the frame. Similarly, the upper rails of the sashes 13 and 14 engage with the intermediate frame members 18, to afford adequate weatherproofing. Thus, flanges 21b of the rails 50 21 tightly engage the flanges 18d of the members 18, while flanges 21d engage the inner faces of flanges 18c. A similar type of engagement is afforded between the upper member 21 of sash 12 and the top horizontal portion of the main 55 frame, while the lower members 21 of all of the sashes form similar tight engagements with the frame members 18 and with the bottom horizontal portion of the main frame. In this completely closed condition, the clutch mechanisms 60 between the lower sash 14 and the travel bars are engaged, that is, the parts of each clutch mechanism occupy a position as shown in Fig. 4. For an opening operation, the operator forces the lower sash outwardly, and since such outward movement is necessarily accompanied by downward movement of the travel bars, all of the sashes move outwardly in unison. When outward movement has continued sufficiently far to cause the cam blocks 56 to ride over the ends 70 of fingers 57, as shown in Fig. 6, the lower sash is disengaged with respect to the travel bars and can now be swung independently. Additional opening movement of the lower sash, independently of the upper sashes, is indicated by Fig. 7, 75

in which it will be noted that the shoe 32 for the lower sash is considerably below the lower ends of the travel bar 47. Upon complete closing of the lower sash, the final part of the closing movement brings the upper ends of the corresponding shoes 32 into engagement with the shoulders 59, which are provided on the travel bars immediately below the cam blocks 56. Thus, for the final part of such closing movement the travel bars are moved upwardly to a sufficient extent to release cam block 56 with respect to finger 57. The travel bars, by their inherent spring, are now being urged against the shoes 32 of the lower sash. However, the upper sashes are still open, although the final part of the closing movement of the lower sash has moved them towards closed position to a slight extent. To close all of the sashes, the operator now again opens the lower sash manually, until the shoes 32 of the lower sash register with recesses 52 in the travel bars, at which time the travel bars move towards each other to again effect an interlocking connection. Closing movement of the lower sash now causes the travel bars to move upwardly to effect conjoint closing of the upper sashes.

It is a particular characteristic of the present invention that, while operative connections are formed between the sashes and the travel bars, such connections do not in any way interfere with the desired functions of the shoes 32, namely, to take up any lateral play between the sashes and the frame irrespective of inaccuracies in manufacture, to enable smooth swinging movement of the sashes at all times and to afford a predetermined amount of friction for the swinging movement. In other words, the sashes are all free floating with respect to the frame and the travel bars, except for the vertical forces applied to them by the travel bars.

Aside from the simplicity of the automatic mechanism afforded, the type of construction disclosed makes it possible to fully reverse all of the sashes to facilitate cleaning of the window panes. In assembling the window, the sections of the travel bars should be so adjusted that the upper sashes are tightly shut upon the frame when picked up and closed by the lower sash. The lower sash is of course provided with suitable locking means which, when engaged, will retain all of the sashes locked and tightly closed against rattling. As previously pointed out, the offset brackets 44 for the upper sashes not only insure adequate forces to open the upper sashes when the travel bars are pulled downwardly, but also insure adequate forces tending to retain the upper sashes closed, thus insuring tightness of the sashes and an absence of rattling.

60 I claim:

1. In a multiple sash window, a rectangular frame including vertical side members which are formed to afford vertical channels, at least two sashes carried by the frame for swinging movement about generally horizontal axes, means including a pair of travel bars extending vertically within said channels for interconnecting the sashes, thereby enabling conjoint movement of the sashes, a disengageable clutch mechanism interposed in said connecting means whereby upon disengagement of said clutch mechanism one of said sashes can be manipulated between open and closed positions independently of the other, a horizontal member extending between the vertical side members of the frame and rig-

idly secured to the same, and cam means serving to effect automatic engagement and disengagement of said clutch mechanism, said cam means including one cam element carried by a travel bar and another operating cam element 5 carried by one end of said horizontal member.

2. In a multiple sash window, a rectangular metal frame, the vertical side members of the same forming vertical channels, at least two sashes carried by the frame, one above the other, vertically movable travel bars disposed within said channels, means forming operative connections between the upper edges of said sashes and said travel bars, supporting arms pivotally connected to the sashes and to the frame whereby when the upper edges of said sashes are moved downwardly by downward movement of the travel bars said sashes are caused to move to open position, said sashes when closed having their end faces overlying said channels, brackets mounted upon the frame and extending inwardly from the plane of the same, support links having their upper ends pivotally connected to the sides of the sashes, the lower ends of said support links being bent to extend 25 inwardly, and means for forming pivotal connections between the lower ends of said arms and said brackets.

3. In a multiple sash window, a rectangular metal frame, the vertical side members of the same forming vertical channels and inner stop flanges, a sash carried by the frame for swinging movement about a generally horizontal axis, vertically movable travel bars disposed in said channels, means operatively connecting the upper corners of the sash with said travel bars, a pair of supporting links, means serving to pivotally connect the upper ends of said links to the sides of the sash, the lower end portions of said links being bent to extend inwardly, brackets 40 carried by the inner faces of the vertical frame members, and means for pivotally connecting the lower ends of the supporting links to said brackets, whereby when the sash is closed against said stop flanges the supporting links, with the exception of said bent end portions, occupy a position between the side edges of the sash and said travel bars, said stop flanges being slotted to accommodate the bent end portions of the supporting links.

4. In a multiple sash window, a rectangular frame, the vertical side members of which are formed to afford vertical channels, at least two sashes carried by the frame, means serving to carry said sashes in said frame for swinging movement about generally horizontal axes, with one sash carried above the other, said means including a pair of shoes for each sash which are slidably carried in said channels, pivot pins carried by the upper corners of each sash serving to pivotally connect the sashes to corresponding pairs of shoes, a spring associated with each pivot pin serving to urge its corresponding shoe into frictional engagement with the adjacent channel, travel bars extending vertically 65 within said channels, and spaced shoulders on the travel bars serving to engage the upper and lower ends of the shoes to apply only vertically directed forces to the same, said shoulders enabling said shoes to align themselves in said channels independently of said travel bars.

5. In a multiple sash window, a rectangular steel frame, the vertical side members of which are formed to afford vertical channels, at least two sashes carried by the frame, means serving 75

to carry said sashes in said frame for swinging movement about generally horizontal axes with one sash above the other, said means including a pair of shoes for each sash, pivot pins carried by the upper corners of each sash and projecting into corresponding shoes, and springs associated with the pivot pins serving to urge the shoes into frictional engagement with said channels, said shoes being channel-shaped in cross-section with their flanges extending into the channels of the frame, travel bars extending vertically through said frame channels and between the flanges of the shoes, and spaced shoulders on the travel bars serving to engage the upper and lower ends of the shoes to apply only vertically directed forces to the same, said shoes being free to align themselves in said channels independently of said connecting means.

6. In a window of the character described, a frame formed of vertical side and top and bottom structural members, the side structural members being formed to provide flanges serving as sash jambs, a sash disposed within the frame, means forming vertically slideable and pivotal connections between the sash and the vertical side members of the frame, a pair of supporting links for the sash, the upper ends of said links being pivotally connected to the side portions of the sash, the lower ends of the links being offset laterally and extended through slots in said flanges, and brackets carried by the vertical side members of the frame and to which the laterally offset ends of the links are pivotally connected, said last named pivotal connections being spaced a substantial distance from the plane of the frame.

7. A window of the character described comprising a frame, said frame being formed of vertical side and top and bottom members, at least two sashes disposed within the frame, vertically reciprocable travelling bars slidably disposed in the vertical side members of the frame, means forming pivotal connections between the upper end of the uppermost sash and said travelling bars, a pair of shoes pivotally connected to the upper end of the lowermost sash and guided for vertical sliding movement in the vertical side members of the frame, said shoes being normally adapted to embrace said bars, means serving to yieldably urge said shoes in opposite directions towards the vertical side members of the frame, fulcrum links pivotally connected to the frame and also to the sides of the sashes, and means to effect the automatic engagement and disengagement of said shoes with said travelling bars through manipulation of the lower sash when the upper sash is in an open position, said last means including means for displacing said shoes in opposite directions.

8. A window of the character described com-

prising a frame having jambs, the inner face of each jamb being formed with a vertical channel; a plurality of sashes mounted in the frame; vertically reciprocable travelling bars disposed in the channels of the guides, pivots on the upper ends of the sashes; a shoe on the outer end of each pivot secured to a travelling bar to guide the same in the channels of the jambs for vertical reciprocation; shoes on the opposite pivots of one sash being detachably engageable with said travelling bars; means on the jambs to effect the automatic engagement and disengagement of said last mentioned shoes with said travelling bars through the manipulation of said one sash relatively to the other sashes in open position; and fulcrum links pivotally connected to the sashes and extended through slots in the jambs into pivotal connection with projecting brackets on the face of the frame.

9. A window of the character described comprising a frame having jambs, the inner face of each jamb being formed with a vertical channel; a plurality of sashes mounted in the frame; vertically reciprocable travelling bars disposed in the channels of the guides; pivots on the upper ends of the sashes, said pivots being yieldable to and from the jambs; a shoe on the outer end of each pivot secured to a travelling bar to guide the same in the channels of the jambs for vertical reciprocation; shoes on the opposite pivots of one sash being detachably engageable with said travelling bars; means on the jambs to effect the automatic engagement and disengagement of said last mentioned shoes with said travelling bars through the manipulation of said one sash when the other sashes are opened; and fulcrum links pivotally connected to the frame and to the sashes.

10. A window of the character described comprising a frame having jambs, the inner face of each jamb being formed with a vertical channel; a plurality of sashes mounted in the frame; vertically reciprocable travelling bars disposed in the channels of the guides; pivots on the upper ends of the sashes, said pivots being yieldable to and from the jambs; a shoe on the outer end of each pivot secured to a travelling bar to guide the same in the channels of the jambs for vertical reciprocation; shoes on the opposite pivots of one sash being detachably engageable with said travelling bars; means on the jambs to effect the automatic engagement and disengagement of said last mentioned shoes with said travelling bars through the manipulation of said one sash when the other sashes are opened; and fulcrum links pivotally connected to the sashes and extended through slots in the jambs into pivotal connection with projecting brackets on the face of the frame.

TOMLINSON I. MOSELEY.

60
